United States Patent Office

Des. 181,564
Patented Nov. 26, 1957

181,564

VENTILATOR FOR TOILET BOWLS

Robert D. Wall, Oak Lawn, Ill., and Carl E. Berry, Pierre, S. Dak., assignors to Sano Industries, Chicago, Ill., a corporation of Illinois

Application March 15, 1956, Serial No. 40,619

Term of patent 3½ years

(Cl. D16—2)

Fig. 1.

Fig. 2.

Figure 1 is a front perspective view of a ventilator for toilet bowls showing our new design.

Figure 2 is a rear perspective view of the ventilator for toilet bowls shown in Fig. 1.

We claim:

The ornamental design for a ventilator for toilet bowls, substantially as shown.
